(57) **CLAIM**

The ornamental design for a laundry bin, as shown and described.

DESCRIPTION

FIG. 1 is a front perspective view of a laundry bin;

FIG. 2 is a top plan view thereof; and,

FIG. 3 is a side perspective view thereof.

The other side view thereof is a mirror image of the side view shown in FIG. 3.

The bag shown in broken lines inserted in the laundry bin in FIGS. 1 and 3 is environmental structure shown for illustrative purposes only and does not form any part of the claimed design.

1 Claim, 3 Drawing Sheets
